CLAIM

The ornamental design of an electronic device having antenna, substantially as shown and described.

DESCRIPTION

FIG. 1 is a front view of an electronic device having antenna in accordance with the present invention;

FIG. 2 is a rear view for the electronic device having antenna in FIG. 1;

FIG. 3 is a left side view thereof;

FIG. 4 is a right side view thereof;

FIG. 5 is a top view thereof; and,

FIG. 6 is a bottom view thereof.

The article is not limited to the scale shown herein. As indicated in the title, the article of manufacture to which the ornamental design has been applied is an electronic device having an antenna. Examples of an electronic device are a computer, a portable or hand-held electronic device, a memory device, an RFID device, an NFC device, a communication device (e.g., cellular phone), a novelty item, a toy, and/or the like.

The broken line in the figure drawings represents unclaimed environment only and forms no part of the claimed design; the dash-dot line represents the unclaimed boundary line and dash-dot-dot line is used to show an isolated enlarged view and forms no part of the claimed design.

1 Claim, 3 Drawing Sheets
